Attorneys.

UNITED STATES PATENT OFFICE.

JOHN B. KIRBY, OF WHITMAN, MASSACHUSETTS.

FLY-TRAP.

1,235,574.

Specification of Letters Patent. Patented Aug. 7, 1917.

Application filed September 18, 1916. Serial No. 120,629.

To all whom it may concern:

Be it known that I, JOHN B. KIRBY, a citizen of the United States, and resident of Whitman, in the county of Plymouth and State of Massachusetts, have invented new and useful Improvements in Fly-Traps, of which the following is a specification.

This invention relates to fly traps and consists in the novel features of construction 10 hereinafter described and particularly pointed out in the claims.

In the accompanying drawings which illustrate the preferred embodiment of the invention,—

15 Figure 1 is a side elevation of the device partly broken away;

Fig. 2 is a longitudinal section of the device; and

20 Fig. 3 is a cross section showing the base in plan.

The body frame upon which a sheet of ordinary sticky fly paper is mounted in cylindrical form, consists as herein shown of a pair of cylindrical supports a , a' , which may 25 be made of sheet metal connected by longitudinal wires or braces a^2 . Each cylindrical support a and a' is provided with a paper engaging tongue a^3 . As many connecting members a^2 as desired may be used to insure 30 sufficient rigidity of the frame, two being shown in the drawings. b is a dished base, the concave side of which engages the end of the paper-receiving body frame. It may be provided if desired with an annular bead 35 or rib b' located just within the periphery of the cylinder a' , forming with the upturned edge of the base b a trough for receiving any of the sticky material which may drip or flow down from the paper.

40 The top member or cover c is dished and is similar in shape to the base, the concave side engaging the upper end of the body frame.

The body frame, base, and cover are 45 separably connected together by means of a rod d which extends through an aperture in the cover c , downward through the body frame, and through an aperture in the base b . The aperture in the base b is a keyhole aperture 50 a^4 , as best shown in Fig. 3, and the lower end of the rod d is provided with a projection d' preferably formed by a bend in the rod which will pass through the keyhole aperture a^4 , and when the rod d is slipped into 55 the narrow part of the keyhole aperture a^4

will engage the base b , thereby separably connecting the parts together.

The upper end of the rod d is provided with an enlargement preferably in the form of a ring d^2 , by which the device may be 60 suspended, and a spring e interposed between the ring d^2 and the cover c yieldingly holds the parts in engagement.

The extremity of each cylinder a and a' may be finished if desired with a turned over 65 lip or bead a^5 .

The fly paper p is secured to the body frame in the form of a cylindrical roll and is held in place by means of the tongues a^3 which are passed through the paper near 70 one edge, and the opposite edge, after the paper has been wrapped around the frame, is slipped under the tongues as best shown in Fig. 3.

I claim:

1. In a fly paper holder, a cylinder upon 75 which the fly paper is wound, dished heads mounted on the ends of said cylinder, said dished heads having bottoms and side walls inclined to said bottoms, said heads being 80 located on the ends of said cylinder and having the dished portions facing each other, and the inclined sides of said heads overlying the paper to protect the same.

2. A fly paper holder comprising a cylindrical frame upon which the fly paper is wound, dished heads disposed at the ends of said frame, said heads having bottoms and side walls making an angle with said bottoms, said heads being located at the ends 90 of said frame and having the dished portions facing each other, the sides of said heads overlying the paper to protect the same, and means for yieldingly holding at least one of said heads against the frame so 95 that it may be retracted from the frame a sufficient distance to permit the winding of a sheet of fly paper around the frame.

3. A fly paper holder comprising a frame 100 upon which the fly paper is wound, dished heads disposed at the ends of said frame, said heads having bottoms and side walls making an angle with said bottoms, said heads being located at the ends of said frame and having the dished portions facing each 105 other, the sides of said heads overlying the paper to protect the same, a rod extending through said frame and one of said heads, the rod connecting with the other head, a stop on the rod outside the other head, and 110

a spring disposed between the stop and head for yieldingly holding the heads against the opposite ends of the frame.

4. A fly paper holder comprising a frame 5 upon which the fly paper is wound, dished heads disposed at the ends of said frame, said heads having bottoms and side walls making an angle with said bottoms, said heads being located at the ends of said frame 10 and having the dished portions facing each

other, the sides of said heads overlying the paper to protect the same, and means extending through the frame into engagement with the heads for detachably holding the heads in operative position with respect to 15 the frame.

Signed by me at Whitman, Mass., this fourteenth day of September, 1916.

JOHN B. KIRBY.
